Primary Examiner — Patricia A Palasik

(57) **CLAIM**

The ornamental design for an industrial robot as shown and described.

DESCRIPTION

1. Industrial robot
- 1.1 : Perspective 1
- 1.2 : Perspective 2
- 1.3 : Perspective 3
- 1.4 : Perspective 4
- 1.5 : Perspective 5
- 1.6 : Perspective 6
- 1.7 : Perspective 7
- 1.8 : Perspective 8
- 1.9 : Front
- 1.10 : Back
- 1.11 : Left
- 1.12 : Right
- 1.13 : Top
- 1.14 : Bottom

Each of 1.1, 1.2, 1.3, 1.4, 1.5, 1.6, 1.7, and 1.8 is a perspective view of an industrial robot; 1.9 is a front elevation view; 1.10 is a back elevation view; 1.11 is a left side elevation view; 1.12 is a right side elevation view; 1.13 is a top plan view;

1.14 is a bottom plan view. The product incorporating the design is mainly used in industrial processing such as picking and placing products or the like; and the drawing
